METHOD OF SHAPING METAL

Joseph G. C. Mantle, Leonia, N. J., assignor, by
mesne assignments, to Bridgeport Thermostat
Company, Inc., Bridgeport, Conn., a corpora-
tion of Delaware

Application May 28, 1932, Serial No. 614,266

2 Claims. (Cl. 153—73)

The present invention relates to improvements in methods of shaping metal and is especially adapted to the production from metal tubing of a great variety of articles such as metal bellows 5 usable for the expansible and contractible elements in thermostats and in pumps and for other purposes wherever suitable.

This application is filed as a continuation in part of my pending United States patent application, Ser. No. 726,671 filed July 18, 1924, Patent 10 #2,044,710, dated June 16, 1936, entitled "Method of and apparatus for making hollow articles", and Ser. No. 749,208 filed Nov. 11, 1924, Patent #2,044,711, dated June 16, 1936, entitled "Corru- 15 gated diaphragm and method of making the same". In addition to which my present application discloses other forms of apparatus for practicing the invention.

The herein method is capable of making metal bellows from thin wall tubing with specially deep corrugations for the bellows folds, the walls of which have the proper temper and cross sectional thickness in the metal thereof to be properly flexible and elastic for efficient operation 20 and long life. Further the method is adapted to make the folds substantially uniform one with another so that the working of the bellows will be distributed substantially equally among all the folds without being concentrated more in 25 some folds than in others to the detriment of the efficiency and life of the bellows.

The herein method comprises initially locking the dies (interchangeably known as dies, die-plates and forming members) to the tube or shell in desired spaced relation by differences in 30 diameter of the shell at and between the dies, which may for example, consist of circumferential creasings or grooves formed in the shell by prebulging or prerolling or in any other suitable manner; and the method further comprises then folding the metal of the shell outwardly 35 between the dies by the combined action of internal fluid pressure and an axial contracting pressure on the shell; and this, without operating, governing or restraining the die plates by any positive means but on the contrary permitting them to float and move toward each other substantially unrestrained except for their aforesaid initial interlocked relation with the shell. 40

As stated, the die plates may be said to float with the shell whereby any section of the shell is free to form into bellows folds ahead of others, and the adjacent dies are free to come together without restraint by any positive means other 45 than that imposed by the shell itself and by

the anchorage of the dies in the creasings thereof.

By "prebulging" is meant initially expanding the shell against the surrounding dies by internal fluid pressure to form differences in diameter in the shell at and between the dies sufficient to lock the dies to the shell. 5

By "prerolling" is meant mechanically forming the differences in diameter of the shell by a rolling, spinning or swaging operation or the like, whereby the dies can be seated in the creasings or grooves thus formed and thereby locked to the tube or shell. 10

In this specification various preferred forms of apparatus are diagrammatically shown for 15 practicing the invention. In one form springs are used between the dies but their resistance to the floating movement of the dies is a freely yielding resistance which is insignificant relatively to the magnitude of the axial shell-contracting pressure and the internal expanding pressure; and is not the resistance of a positive 20 rigidly acting device.

Another form shows shouldered spacing rods which in their initial position engage the die 25 plates and automatically space them evenly and properly along the tube or shell. However, these spacer rods during the subsequent bellows fold operation are moved out of contact with the die-plates and therefore, have no restraining 30 effect upon their movement; and this is irrespective of whether one pair of dies may move toward each other to form a bellows fold ahead of others. 35

In still another form, spacer blocks are temporarily located between the dies to position them evenly and properly along the tube or shell until it has been prebulged by internal fluid pressure; but after that these spacer blocks are removed and the subsequent bellows-fold forming opera- 40

tion takes place while the dies are free to move toward one another unrestrained by any positive means other than the creasings or differences in diameter of the shell with which they are interlocked. 45

Mantle, Serial No. 726,671, filed July 18, 1924

Except for typographical and immaterial corrections, the following excerpts pertaining to the present invention are quoted from this application as filed. Also Figs. 1 to 9 inclusive, in the drawings are copied from said application as filed. 50

This invention is a method of and apparatus for the formation of articles from shells or tubes 55

of ductile material. The shells and tubes are usually drawn from sheet material and are either flanged or plain.

The object of this invention is to rapidly and 5 economically transform them into such shapes which, in general, could only hitherto be done by repeated annealings and operations, or, by first forming portions and then joining them together to form the whole.

10 In the drawings:

Figures 1, 2 and 3 show a flanged shell at different stages of the operation.

Figures 4, 5 and 6 are separate views of parts 15 of the contractible mold shown in Figures 1, 2 and 3.

Figures 7, 8 and 9 show a flanged shell at different stages of the operation, the whole so arranged that the internal fluid pressure may be applied and the contraction of the contractible 20 mold effected by the punch holder or slide of an ordinary power press.

Referring to Figure 1: The flanged shell 1 is supported in a contractible-mold consisting of parts 2, 3 and 4. Each of the parts 3 and 4 25 consists of two complementary pieces, as shown in Figure 4, and they are supported and held together in holders 5 and 6. Figure 5 shows a holder; each holder has an annular portion and is provided with cut-away portions 7 corresponding to lugs 8 on the mold-parts 3 and 4, so that they may be placed therein and when given a slight twist they are supported and held together or prevented from spreading apart. Each holder has an attached set of springs 9, the 30 free ends of which are adapted to fit into grooves 10 on the upper surfaces of the holders 5 and the mold-part 2. These springs sustain the holders in correct relation to each other, and also act as guides in preventing lateral movement. The 35 holder 6 is secured to a top-plate 11 which is provided with a tube 12 which telescopes into a reservoir 13 containing fluid under pressure. Between the reservoir 13 and the top plate 11 is a removable stop-piece 14. The stop-piece 14 having 40 been removed, the top plate slid up to the reservoir, the holders with their mold-parts assembled on the mold-part 2, the shell placed therein, the holder 6 secured to the top plate and the stop-piece slid into place, the whole is 45 ready for the operation, which is as follows:

Fluid, usually water, under a pressure varying in accordance to the nature of the shell, is permitted to pass through the tube 12 and fill the shell, and then by reason thereof and on account 50 of the shell being longitudinally confined, a change in shape occurs, as shown in Figure 2, viz., bulgings of the shell between the contacts of the mold-parts and creasings of the shell at the intermediate parts in contact with the mold-parts, as respectively shown at 15 and 16 in Figure 2. Subsequently and whilst under sustained fluid pressure the contractible-mold is 55 compressed, preferably by a downward pressure and applied by mechanical means to the top plate 11, until the parts are positioned as shown in Figure 3, or, to any desired intermediate position. In the example shown, the mold-parts are equi-distant, and on account of the creasings 16 they approach each other equi-distantly during 60 the whole of the compression of the contractible-mold.

In certain instances it is preferable to form these creasings (by rolling or otherwise) prior to the placement of the shell in the contractible-mold operation, in which case the compression of 65

the contractible-mold may commence at the same time as the internal fluid pressure.

The shell or tube filled with a liquid, usually water, is placed in the contractible-mold and the internal fluid pressure is produced in the Figs. 5 1-3 apparatus by the downward movement of a plunger carried by the punch-holder or slide of the press, against and into the water or other liquid contained in the shell and at the same time the punch-holder or slide of the press operates 10 mechanism which immediately afterwards compresses the contractible mold.

Referring to Figures 7, 8 and 9, the top plate 11 is provided with a sleeve 17 through which 15 operates the plunger 18 attached to the punch-holder of the press. The sleeve 17 is provided with lugs 19 adapted to be acted upon by mechanism operated by the punch-holder of the press.

In the examples so far described, leakage of 20 the fluid is prevented by the nipping of the flange of the shell between the top plate and the uppermost holder. When a flangeless shell is used, some other suitable adaptation or arrangement as shown may be employed to prevent leakage.

The mold-parts may be positioned at their 25 correct, though unequal, distances by means as shown in Figure 1, for the creasings of the shell tend and usually suffice to retain the correct proportionate spacings during the closing together of the mold-parts. But it is often desirable, or 30 even necessary, to provide means which positively or rigidly control this spacing of the mold-parts throughout the operation.

Manfile, Serial No. 749,208, filed November 35 1924

Except for typographical and immaterial corrections, the following excerpts pertaining to the present invention are quoted from this application as filed. Also Figs. 10 to 14 inclusive in the 40 drawings are copied from said application as filed, except for immaterial omissions in some of said figures.

This invention relates to expandible-contractible metal elements such as are adapted for use 45 in pumps, motors, or in pressure-sensitive or heat-sensitive devices in general.

The method of manufacture consists in first forming a shell from sheet metal, then forming the outwardly projecting gasket-flange, and then 50 converting the shell to its final shape by the method and apparatus described in my pending application Serial No. 726,671, entitled "Method of and apparatus for making hollow articles", and as will be further hereinafter described in 55 connection with the accompanying drawings.

Figure 10 shows the gasket-flanged shell after having undergone a rolling operation.

Figures 11 to 14, inclusive, show different forms 60 of the complete articles when converted into final shape (by my "Method of and apparatus for making hollow articles").

When the inner curves of the corrugations are nearer the axis of the diaphragm than the inner surface of the opening 116', then the shell is 65 recessed inwardly, as is shown at 116 in Figure 10 by a rolling operation. The manner and means for rolling these recesses is well known, and needs no explanation.

To convert either of the shells shown in Figure 9 (this is not Fig. 9 of the present application but refers to a figure in Ser. 749,208, here omitted, showing an ungrooved cylindrical shell) and Figure 10 (showing pregrooved shell) to either one of the final shapes shown in Figures 11, 12, 13 and 70 75

14, reference is made to my aforesaid prior application.

It can be readily understood that with a shell of given diameter and material, a deeper final 5 corrugation may be obtained by a prior corrugating of the shell, as shown in Figure 10. Also, as a rolling operation increases the hardness, a higher temper is induced in the corrugation nearest the axis. By inspection of Figure 8 in my 10 prior application for "Method of and apparatus for making hollow articles", Serial No. 726,671, it will be seen that when the shell is placed in a contractible-mold subjected to internal fluid pressure there is an analogy to a uniformly loaded 15 and equidistantly supported beam, and that the stress is greatest, and consequently the shell is thinnest and hardest, at the portions midway between the supporting surface of the mold parts of the contractible mold and is thicker and softer 20 the nearer it is to the mold parts. Now, the degree of this variation of hardness, due to the thinning of the material, is of course dependent upon the nature of the material and upon the applied pressure. Were the material soft pure 25 rubber, there would be practically no variation in thickness. With low brass (low percentage of zinc), it is found that there is but a very gradual increase in thickness and decrease in hardness of the material from the outer to the inner corrugations, and that they are fairly uniform 30 throughout their lengths. By the prior rolling of the inner corrugations, as in Figure 10 of this application, and by suitably adjusting the internal fluid pressure, the inner and outer corrugations 35 may be given any relative degree of hardness as may be desired. At the completion of the operation of corrugating the diaphragm, the thickness of the material throughout the length of the corrugations is appreciably less than that of the 40 original wall. The amount of this diminution is dependent upon the kind of material. It is found that brass consisting of 85% copper, 15% zinc, may be safely stretched fully 20%, or, in other 45 words, until its thickness is about 83% of its original thickness (by my "Method of and apparatus for making hollow articles"). This amount of stretch is well within its safe limit, for a series of diaphragms so made have already performed over 50,000,000 pumping operations (in extension and contraction), and are now apparently still in sound condition.

In forming a diaphragm where the corrugations are required to be equidistant, it has been found to be unnecessary to provide means for positively controlling the relative movements of the mold parts towards each other during the operation of forming the corrugations, but, when they are required to be unequally spaced, or are of varying forms, then such positively controlling 60 means are necessary.

It is to be understood that these diaphragms may be made of any suitable material for the purpose required.

Method in re Figures 15-17 inclusive

65 Figs. 15-17 inclusive show diagrammatically another form of apparatus or collapsible mold, for practicing the invention wherein:

Fig. 15 is a front elevation, partly in vertical 70 section, of the apparatus, with the parts hinged open and indicates a shell in position by the full lines ready for the parts to be closed and locked and for the prebulging operation, and after that for the bellows-fold forming operation.

75 Fig. 16 is a plan view of the lower head plate,

the hinging-open thereof being indicated by the dotted lines, this view also indicating the spacer blocks in plan; and

Fig. 17 is a diagrammatic view showing, in vertical section partly in elevation, a form of fluid 5 pressure creating means shown connected to a fragment of the head portion of the apparatus of Fig. 15.

The apparatus comprises a base plate 40, the top of which may be formed with a circular recess 10 41 adapted to receive the bottom of the cup-shaped shell 42. The head of the apparatus consists of two superposed plates 43 and 44 adapted to clamp between them the flange 42a at the mouth of the shell and the rubber gasket 45. 15

Parallel rods 46 pass through aligned holes in the head and base plates. The ends of these rods are screw threaded to receive nuts as shown. The nuts 47 and pins 48 serve to clamp the flange of the shell and the gasket 45 as aforesaid, fluid-tight between the two head plates 43 and 44. 20 These rods 46 slide freely through the holes in the base plate 40; and the nuts 49 on their lower ends serve to hold this plate from separating from the rods. 25

The lower head plate 43 is made in two partable hinged together sections. What may be termed the main section 43a is the section through which the rods 46 pass. The other section 43b is hinged or pivoted at 50 to the main section to 30 swing in the plane of the other section. This lower head plate 43 is also a die and for this purpose its two sections are formed with complementary circular recesses whose rims 51 when the sections are together, constitute a circular 35 bellows-fold forming member or die circumferentially surrounding the shell 42. 52 is a latch for releasably locking together the free ends of the two sections of the lower head plate. This latch is located in a groove in the end of the main 40 section 43a and swings or pivots in the plane thereof on a pin 53. The latch is notched at 52a to engage a pin 54 in the grooved end of the other section 43b.

The detail of the hinge connection between 45 the sections 43a and 43b is best shown in Fig. 16 when compared with Fig. 15 from which it will be seen that the swinging section 43b has a thinner rigid extension 43c extending at a right angle therefrom, swinging about the pin 50 and 50 receivable like a knife blade snugly in and out of a groove in the end of the main section 43a. This construction gives rigidity to the two sections of the lower base plate in the plane thereof as does also the latch 52 locatable also like 55 a knife-blade snugly in its groove as above described.

When the sections 43a and 43b are latched together they abut along their inner edges as shown by the full lines in Fig. 16. Again referring to the plan view Fig. 16, it will be seen that one section, which as shown may be the swinging section 43b, is formed at its inner longitudinal edge with a projecting portion or portions 55 shaped to be received snugly into a corresponding recess or recesses in the inner longitudinal edge of the other section 43a, whereby these sections when in latched together relation are restrained from longitudinal movement or slip on each other. 65

Hinged partable die plates 56 are slidably mounted on the guide rods 46. Generally speaking, each of these is constructed similarly to the lower head plate 43 just described. Thus, each die plate comprises a main section 56a (through 70 75

which are the holes for the guide rods 46), and further comprises another section 56b hinged to the main section at 57 to swing in the plane of the main section. Also the two sections of each die plate are formed with complementary circular recesses whose rims 58 together make a circular bellows-fold forming member or die circumferentially surrounding the shell when positioned in the apparatus. Also latch means 59 is provided in connection with each die plate for releasably latching together its two sections. Also the details of the hinge connection between the sections 56a and 56b of the die plates is or may be the same as already shown and described in connection with the lower head plate; and the same is true as to the details of the aforesaid latch means 59; and as to the interlocking of the inner longitudinal edges of the sections against longitudinal slip on each other.

With this form of the apparatus, the shell is preferably initially pre-bulged in the apparatus before forming the bellows folds. In order that the prebulging shall lock the die plates to the shell properly spaced along the shell, I provide and insert suitable spacer blocks or rectangular cross-sectioned members 60 between them. After the shell has been prebulged by the internal fluid pressure into interlocking relation with the dies, it will be understood that these spacer blocks 60 are removed preparatory to the next operation which is the forming of the bellows folds.

61 designates a plug screwed into a threaded hole through the upper head plate 44, located over the mouth of the shell when the latter is in position in the apparatus. This plug has an axial hole through it or bore arranged to seat a ball or other suitable valve 62 at or towards the outer end of the plug backed up by a spring 63 for normally seating the valve against its seat. The hollow plug 61 is provided with pins 64 for coupling it and the shell with a liquid or fluid pressure creating device or means 65. One simple kind of such means usable for the purposes of the invention is conventionally shown in Figs. 15 and 17, and is commonly known as a grease gun. It comprises a cylinder A and a piston B having a screw-threaded piston rod C which projects through a correspondingly threaded hole in the head of the cylinder and is provided with an operating handle D at its free end. Connected with the other end of the cylinder is a flexible non-collapsible tube E having a coupling F at its free end. This coupling is a tubular member receivable over the plug 61 and has bayonet slots G in its walls engageable with the pins 64 on the plug whereby due to this and an intervening gasket and other well known adaptations not necessary to be shown a liquid tight under pressure connection is made between the grease gun 65 and the interior of the shell in the apparatus. Assuming that the grease gun is connected as described with the tubular plug 61 of the apparatus, and that it is filled with grease or oil and that the shell 42 is similarly filled, the gun is operated by turning the handle D to screw the piston forward to force more of the contents of the cylinder past the valve 62 of the plug and into the shell to create the desired hydraulic pressure therein as and for the purposes of the invention as hereinafter described.

The aforesaid apparatus of Figs. 15-17 inclusive is used to practice the invention with prebulging as follows.

75 The nuts 47 will be removed and the upper

head plate 44 taken off. The spacer blocks 60 will then be inserted as shown in Fig. 15 to space the dies properly, which is usually equidistantly from one another along the shell. Also the lower head plate 43 and all of the die plates 56 will be unlatched and opened up on their hinges or pivots. The flanged cup or shell 42, either then or later filled with a suitable liquid, oil or grease, is then inserted in the apparatus as in Fig. 15 with its flange 42a supported by the die portion 51 of the lower head plate 43 and with its bottom located either somewhat above or in the recess 41 of the base plate. The sections of the die plates and of the lower head plate will then be closed about the shell and latched. The upper head plate 44 can now be put into position and the nuts 47 applied and screwed down so as to clamp fluid-tight the flange 42a of the shell and the gasket 45 between the upper and lower head plates. The liquid or fluid pressure creating device 65 will then be operated to create an internal fluid pressure within the shell just sufficient to bulge or expand its walls outwardly against the dies to crease said walls at the dies sufficiently to lock the die plates to the shell. The dotted lines 42b in Fig. 15 indicate these creasings which for purposes of clear illustration have been exaggerated. The die plates being now locked to the shell by the aforesaid so-called prebulging operation in the spaced relation accomplished by the spacer blocks 60, these latter having then served their purpose are removed so that thereafter the die plates are free to float unrestrained by any means other than the shell to which they are locked by the creasings thereof. The pressure creating device 65 may then be uncoupled from the plug 61 without, however, affecting the fluid pressure in the shell which will be maintained by the automatically closing valve 62 of the plug.

The head of the apparatus will now be forced 40 toward the base by the use of any means suitable for the purpose such as a press whereby the shell becomes bulged or expanded outwardly into corrugations or bellows folds between the dies by the combined forces of the axial contracting pressure due to the press and the internal fluid pressure. During this endwise contraction of the shell, the internal pressure therein is maintained in sufficient amount to keep the walls of the shell in tension and compel the metal between 50 the dies to roll or fold outwardly along curved lines. Crimping of the corrugations between the dies is thus avoided. As the tube or shell contracts in length and the folds are formed, its capacity is decreased and the fluid pressure therein rises. The valve 62 may be momentarily 55 opened at intervals by pressing it inwardly so as suitably to relieve excessive fluid pressure within the shell. It is preferable to maintain this pressure substantially uniform during the bellows-fold forming operation and substantially 60 as it was during the prebulging step. However, it will be understood that there is considerable latitude as to the pressures which may be used.

Because the spacer blocks have been removed 65 as a preliminary to the bellows-fold forming operation, and because there is no other positive means except the creasings in the shell restraining the free movement of the die plates, it will be evident that any of the bellows folds is free to 70 form ahead of the others unrestrained except for its interlocked relation with the creased shell.

Method in re Figures 18-20 inclusive

These figures show diagrammatically still 75

snugly through it the base of the pressure relief device 91. In effect the gasket is an inverted cone, in other words, its lower side inclines upwardly and outwardly from the center towards 5 the periphery.

To practice the invention with this apparatus, Figs. 18 to 20, the nuts 81, and the upper part 10 of the head will be removed. The apparatus being assumed to be resting on a table or bench 15 in vertical position as in Fig. 18, the rods 73 loose in the base 70 with their lower ends bearing against the top of the table will uphold the lower plate 76 of the head; and at this time the shoulders 87a of the spacer rods 87 will uphold 20 the die-plates 83 as indicated in Fig. 18 in properly spaced relation. The swinging sections of the die-plates 83 and of the lower head plate 76 being assumed to be open, the pregrooved shell 25 72 can then be inserted laterally into the apparatus into the position shown in Fig. 18 with the grooves 72b of the shell fitting and receiving the bellows-fold forming rims 80 and 85 of the main sections of the die-plates and of the lower head plate. The hinged sections of all of these will 30 then be closed and latched to the main sections. The shell or cup will then be filled with kerosene or any other suitable liquid. The upper part 35 75 of the head will then be placed in position on the rods 73 and the nuts 81 will be applied and tightened to clamp the gasket 82 and the flange 72a of the shell fluid-tight between the upper and lower parts of the head. During the foregoing, liquid will be displaced from the cup by the dipping of the pressure relief device 40 91 therein and will overflow at the brim of the cup leaving the cup including the space covered over by the gasket entirely filled with the liquid when the gasket 82 begins to be compressed, after which time no more liquid can escape at 45 the brim or flange of the cup. During the subsequent tightening of the nuts 80, the further compression of the thick rubber gasket 82 puts said liquid under compression and applies an initial hydraulic pressure to the interior of the cup.

The apparatus may now be stood on the bed plate of a drill press or the like with the lower ends of the rods 73 located to pass freely through 50 holes or slots in said bed plate and so that the lower ends of the spacer rods 87 can do likewise. At this time, because the rods 73 are no longer supported at their lower ends, the shell or cup bottoms itself in the recess 71 of the base 55 of the apparatus. The stem 75a of the head of the apparatus will then be inserted in the tool-holding chuck of the press.

The bellows-fold forming operation can now 60 take place by operating the press to force down the head of the apparatus towards the base. This applies axial contracting force to the shell; and at the same time hydraulic pressure within 65 the shell acts outwardly against the walls. The result is that the walls of the shell fold outwardly between the dies into bellows folds 72c. Coincident with the formation of these folds, the 70 descending head shortens the overall height of the shell; and the dies, due solely to their engagement with the grooves of the shell, are carried closer together until they are collapsed, one 75 on top of the other, at the bottom of the apparatus when all of the bellows-folds have been formed.

In this forming operation, one bellows fold is 75 entirely free to form independently and ahead of others without any restraint other than that

imposed by the shell itself and the anchorage of the dies in the grooves thereof. The shouldered spacer rods by their design and mode of operation have no effective contact with the die-plates after the head starts to descend, because immediately the shoulders of the rods progressively move further and further away from any supporting contact with the die plates. 5

As the shell shortens, its capacity is decreased and the internal hydraulic pressure increases; 10 and this is automatically relieved by the pressure relief device 91 to prevent an excessive pressure from overstressing or rupturing the metal. To this end, the spring 95 of the pressure relief device is initially set by adjusting the hollow 15 screw plug 97 so as to permit the valve 94 to open and relieve the hydraulic pressure whenever it exceeds that necessary, suitable or preferred to properly form the bellows folds acting in conjunction with the axial contracting pressure on 20 the shell.

It will be seen that in the method practiced as described with all forms of the apparatus, the dies are initially interlocked with the tube or shell by differences in diameter formed therein 25 by a prebulging or prerolling or other suitable operation; and then in the subsequent bellows-fold forming operation, the dies float with the tube unrestrained by any positive means other than their aforesaid interlocked relation with 30 the tube.

An advantage of prerolling is that it is a means of satisfactorily adding to the deepness of the folds and imparting desirable temper thereto as explained. An advantage of prebulging is that 35 it permits the successive steps of the method to be practiced in one and the same apparatus to produce the complete product.

The use of this method is not restricted to 40 shells and tubes of a circular cross section. Moreover by modifications well known in the art, the apparatus may be modified to take bottomless tubes or shells. It is also obvious that the contractile mold made up of the described 45 die plates and head and base members may have any suitable transverse or longitudinal internal form either curved or rectilinear. Neither is the method limited to uniform or concentric enlargements around the axis of a shell or tube. In other words, the method is not restricted to producing symmetrical shapes only. Instead of liquid pressure, it is possible to use fluid gaseous 50 pressure.

It will be understood that a pregrooved or pre- 55 rolled shell may be used with the apparatus of Fig. 15; and that the prebulging process described in connection with Fig. 15 may be carried out with the apparatus of Fig. 18.

It will be appreciated that the above disclosures are given by way of example and that the 60 foregoing and other modifications may be made without departing from the scope and spirit of the invention.

What I claim is:

1. A method of making hollow metal corrugated articles, which comprises placing a tube in a vertically arranged contractile mold having movable and spaced mold parts and locating the mold parts without positively holding the mold parts before the mold parts are locked to the 70 tube, bulging the tube by applying internal fluid pressure thereto to form differences in diameter in the tube sufficient to interlock with the mold parts, and then contracting the tube in length to form corrugations therein by the combined 75

another form of apparatus or collapsible mold for practicing the invention wherein:—

Figure 18 is a front elevation partly in vertical section of this apparatus, with the parts hinged open and further shows a pregrooved shell in position ready to have the mold parts closed together and locked to the shell preparatory to the bellows-fold forming operation.

Figure 19 shows the apparatus or mold of Fig. 10 18 collapsed and shows the walls of the shell formed into bellows folds; and,

Figure 20 shows the pressure relief valve of Fig. 18 in vertical section and on a larger scale in connection with a fragment of the head of the apparatus.

This apparatus is similar in many respects to that just described, but provides shouldered spacing rods 87 for initially automatically spacing the dies to correspond with and fit into prerolled 20 grooves or creasings of the shell when inserted in the apparatus. Moreover during the bellows-fold forming operation, these shouldered spacing rods are automatically moved and kept out of any interfering position with the die plates.

Briefly, this apparatus, like the other, comprises a base 70 in the top of which is formed a circular recess 71 wherein to bottom the cup-shaped shell 72. The head of the apparatus, as before, is supported on parallel rods 73—73 which 25 are slidable in vertical holes through the base on opposite sides of the recess therein. The head 74, as before, consists of two superposed parts, an upper cylindrical part 75 loose on the rods 73 and a lower part or plate 76 pinned at 77 or 30 otherwise permanently fastened to the rods. The lower head-plate 76, as before, consists of two hinged partable sections. The main section 76a, as before, is the part through which rods 73 pass and which is permanently fastened 35 to the rods. The other section 76b, as before, is hinged at 78 to the main section to swing in the same plane. A latch 79 releasably locks together the sections of the lower head plate. The sections, as before, have complementary circular 40 recesses whose rims 80, when the sections are together, constitute a circular bellows-fold forming member or die surrounding the shell.

As before, the flange 72a at the mouth of the shell is adapted to be received and clamped between the upper and lower head parts by taking up on the nuts 81 on the screw-threaded upper ends of the rods. A rubber gasket 82, although differing in detail, is interposed as in the other apparatus to make the joint fluid tight.

As before, hinged partable die-plates 83 are 55 slidably mounted on the guide rods 73. Also each die-plate consists of a main section 83a wherein are the holes for the guide rods; and further consists of another section 83b hinged 60 to the main section at 84 to swing in the same plane. Also the two sections of each die-plate are formed with complementary recesses whose rims 85 together make a circular bellows-fold forming member or die adapted to enclose and 65 surround the shell. As before, latch means 86 including related parts is provided in connection with each die plate for releasably locking together its two sections, like the latch 52 and related parts in Fig. 16.

As stated, the tube or shell 72 preferably used with this type of apparatus will be of the pre-rolled type, (compare Figure 10) in other words, will have been already inwardly grooved by a rolling operation or the like with grooves 72b 70 corresponding in spacing with the requirements

of the finished article, which in the case of a bellows will be usually an equidistant spacing. In this case there will be as many die-plates as there are grooves in the prerolled shell; and preferably means will be provided for automatically properly spacing the dies relatively to one another so that when the pregrooved shell is inserted in the apparatus and the partable die-plates are closed, these will automatically seat themselves in the grooves.

Such automatic spacing means may of course take a variety of forms. That shown consists of a pair of shouldered rods 87 depending from the head of the apparatus to which the rods are secured between shoulders on the rods and nuts 15 on their screw-threaded upper ends. These rods pass through holes 88 in the main sections of all of the die-plates, said holes progressively increasing in diameter as shown from the top die to the bottom die. The rods are provided with 20 shoulders 87a, one for each die-plate, which similarly increase in diameter so that each shoulder can pass freely through the hole in the die-plate below it whereas it is too large to pass through the hole in its own die-plate, namely the die 25 which it is intended to support. The result is that when the head of the apparatus has been raised into its starting position preliminary to the bellows-fold forming operation, it supports the shouldered spacer rods 87 in a position (compare Fig. 18) wherein the shoulders of these rods in turn support and properly space the die plates 30 83 so as to fit automatically into the grooves of the prerolled shell when the latter is inserted sideways into the apparatus.

89 is a duct extending through the head-part 75 from its bottom through to its periphery. This duct is for relieving the hydraulic pressure within the shell during the bellows-fold forming operation, and for this purpose its inner end is 40 screw-threaded to make tight connection with the externally threaded stem 90 of a pressure-relief device of any desired or preferred form. The particular pressure-relief device 91 shown diagrammatically herein, comprises an axially hollow casing 92 formed at its lower end with a seat 93 for the ball valve 94. In this casing is located a coil spring 95, adjustable as to compression, loosely surrounding the rod 96 and located between a peripherally serrated collar 96a on said rod and an axially hollow plug 97 in the upper end of the casing 92, said plug for up and down adjustment having screw-threaded connection with internal screw threads of the casing in order to adjust the compression of the spring. 45 This hollow plug 97 at its upper end has a screw driver slot 97a for adjusting it. The serrated collar 96a bears on the ball valve.

The following further details in connection with the particular apparatus illustrated in Figs. 18-20 should be mentioned. Thus the base 70 has vertical holes 70a for loosely receiving the lower ends of the shouldered rods 87 through them. The rods 73 are preferably long enough so that when the apparatus is supported uprightly on a 50 table or bench, these rods upheld by the bench in turn support the head of the apparatus as well as the shouldered spacer rods 87 and the die-plates 83, as indicated in Fig. 18, whereby the pregrooved shell 72 can be inserted laterally into 55 position in the previously opened dies with its bottom preferably clearing the recess in the bottom plate 70 so as to permit the direct lateral insertion of the shell. The gasket 82 is a rather thick rubber disk having a center hole receiving 60 70 75

action of an axial contracting pressure applied to one end mold part of the contractible mold and to one end of the tube and an internal fluid pressure within such tube while permitting the mold parts to move with the tube during the contracting thereof.

5 2. A method of making hollow metal corrugated articles, which comprises positioning a hollow article in a vertically arranged contractible mold having spaced mold parts and locating the mold parts without positively holding the mold parts before the mold parts are locked to the hollow article, interlocking the mold parts in

encircling relation with a hollow article by means of differences in diameter in the hollow article at and between the mold parts, and then forming the portions of the hollow article between the mold parts into corrugations by the combined action of an internal fluid pressure within the hollow article and an axial contracting pressure applied to one end of the hollow article while permitting movement of the mold parts with the hollow article during contracting 10 thereof.
